2 Sheets-Sheet 2

UNITED STATES PATENT OFFICE.

GEORGE A. MEARS, OF NEWBERRY, PENNSYLVANIA.

SAFETY DEVICE FOR MOVING-PICTURE BOOTHS.

Application filed June 11, 1926. Serial No. 115,309.

This invention relates to a safety device designed primarily for installation in picture projecting booths, one of the objects being to provide a means whereby should a 5 film become ignited in a projecting machine or on the rewinder, mechanism will be released to automatically close the shutters of the port holes, to cut off the current to the projecting machines, to automatically start 10 an exhaust fan, and to release a supply of fire extinguishing fluid so that it will be directed into the machine or machines where the fire is located.

A further object is to provide apparatus 15 of this character which can be installed readily and, when installed, will in no way interfere with the operator in the performance of his usual duties.

A further object is to provide a means 20 under the control of the operator whereby, in an emergency, he can release the various parts of the apparatus so as to operate in the same manner as though a fire had occurred.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed may be made within the scope of what is claimed, without departing from the spirit of the invention.

In the accompanying drawings, the preferred form of the invention has been shown. 35

In said drawings,

Figure 1 is a plan view of the complete apparatus, the booths in which it is located being shown in section.

Figure 2 is a side elevation of the apparatus, the booth being shown in section.

Figure 3 is a side elevation of the latch mechanism.

Figure 4 is a bottom plan view thereof.

Figure 5 is an end elevation.

Figure 6 is a section on line 6--6, Figure 3, the latch lever being removed.

Figure 7 is a perspective view of one of the inflammable anchors used in connection 50 with the apparatus.

Figure 8 is a perspective view showing an arrangement of an inflammable anchor in connection with the rewinding mechanism.

Figure 9 is a section through the box containing a switch for controlling the current to the projecting machine.

Figure 10 is a similar view showing a switch for controlling the current to the exhaust fan.

Referring to the figures by characters of reference A designates a projection booth having port holes B such as commonly employed. Within the booth and back of some of these port holes are located projecting machines C and at any suitable point 65 within the booth is a switch box D containing a switch for controlling the light in the house and the flow of current to the projecting machines. Another switch box E is located in the booth and contains a switch 70 for controlling the flow of current to a suitably located exhaust fan which, when operated, will withdraw fumes from the booth. Film rewinding mechanism is located in the booth as shown at F. The apparatus 75 constituting the present invention is located entirely within the booth and the principal part thereof comprises a latch of novel construction which has been shown in detail in Figures 3 to 6 inclusive. This latch includes 80 an attaching plate 1 adapted to be secured to the ceiling of the booth or to any other elevated structure. Depending from one end portion of the attaching plate is a tongue 2 provided, near its lower end, with a transverse slot 3. A finger 4 is extended 85 downwardly from the attaching plate between the tongue 2 and the adjacent end of the plate and is extended outwardly away from the tongue for engagement by one end of a supporting wire 5 which is stretched along the booth near the ceiling and can be attached to one wall thereof as shown particularly in Figures 1 and 2. A slide 6 is mounted on the tongue and has side ears 7 90 which engage the side edges of the tongue. Slots 8 are formed in the slide and receive holding screws 9 projecting from the tongue. Thus the slide can be moved upwardly and downwardly upon the tongue and will be 95 properly guided by the screws 9 and the side ears or lugs 7. A slot 10 is formed transversely within the slide and is adapted 100 normally to register with a portion of the slot 3.

A ledge is extended from the upper edge of the slide 6 and is contacted by one end of a cam lever 12 pivotally connected to the tongue 2 as shown at 13. A cord 14 is attached to the upper arm of this lever 110 and is extended transversely across the booth A and attached to one of the walls there-

of, this cord, which can be known as an emergency cord being located where it can be easily reached and pulled by the occupant of the booth.

5 A bail 15 is normally mounted on the finger 4 and is extended upwardly from the sides of an elongated loop 16 one end portion of which is contracted so as to be insertable freely into the slots 10 and 3. The 10 other end of the loop is enlarged as indicated at 17 and is supported below the finger 4 under normal conditions. A bracket 18 extends downwardly from the attaching strip 1 and pivotally mounted therein is a 15 latch lever 19 having a short arm 20 from which depends a short nose 21. To the other or long arm of the latch lever is connected a weight 22 or, if preferred, this weight can be made integral with the lever. An eye 20 23 is supported by the attaching strip 1 close to the weighted end of the latch lever and is designed to support a release cord 24 one end of which is attached to the lever 19 so as to normally support the lever with nose 25 21 projecting into the loop 16.

Attached to each projecting machine C at a point close to the film therein is a plate 25 provided with an aperture 26. A strip 27 of celluloid or other highly inflammable material is looped about the apertured portion of this plate. To each end of the inflammable strip 27 is secured a reinforcing plate 28 having an opening 29 therein. One end of a cord 30 is extended through and secured within the apertures 29 at the two ends of the strip 27. This cord 30 is extended upwardly from the strip 27 through a guide 31 suspended from the ceiling of the booth and is then extended loosely 35 through a guide ring 32 and a stationary guide 33. One of these inflammable anchoring devices in the form of a strip 27 is located in each projector and the two ends of the cord 30 are attached to the respective anchoring strips 27. The releasing cord 24 is extended through a guide 34 and is then looped through the ring 32 so as to support it. From this ring 32 the release cord 24 is extended through a guide 35 and 40 through another ring 36 located above and adjacent to the rewinding mechanism F. An elongated bracket 37 is secured close to and above the rewinding mechanism and has apertures 38 in the ends thereof. Below 45 each of these apertures is an angular extension 39 likewise formed with an aperture 40 arranged close to the reels of the rewinding mechanism. An inflammable strip of celluloid or the like indicated at 41 and which constitutes an anchor is looped 50 about the apertured portion 40 of each extension 39 and, like the anchor 27, has reinforcing plates 42 upon the end portions thereof provided with apertures 43. One 55 end of the releasing cord 24 is attached to

the reinforcing plates 42 of one of these anchors 41. Another cord 44 is attached to the ring 36 and also to the reinforcing plates 42 of the other anchoring strip 41. Because of the angular arrangement of the 70 release cord 24 and of the projector cord 30 it will be apparent that should any one of the anchor strips 27 or 41 become ignited and thereby release its cord, the cord 24 will be permitted to release latch lever 19 75 with the result that weight 22 will drop. This action will take place should either of the anchor strips 27 become ignited by a burning film in either projector or should either of the anchor strips 41 become ignited 80 by the film being rewound at F.

A shutter 38 is adapted to close each of the port holes B, these shutters being slidably mounted and being normally suspended above the port holes by cords 39 extending 85 upwardly through guides 40 and thence along the ceiling to the enlarged portion 17 of loop 16 to which the cords are attached.

Nozzles 41' are located where they will direct jets of fluid upon the films in the projectors and these nozzles are all in communication with a pipe 42' designed to supply them with a fire extinguishing fluid, a valve 43' normally closes the pipe 42' but has a weight 44' for operating it, when released, 90 thereby to open the valve. This weight is normally supported by a cord 45 extended through a guide 46 and attached to the loop 17.

The switch box D contains a movable switch member 47 provided with a weight 48. This switch member is normally in closed position and thus permits current to flow to the projecting machines. A cord 49 is attached to the weighted end of the member 47 and extends upwardly through a guide 50 and thence along the ceiling of the booth to the loop enlargement 17. Within the switch box E is located a movable switch member 51 to which is connected a weight 52. This switch member is normally in open position and a cord 53 extends from the weighted end thereof through a suitable guide 54 to the enlarged end 17 of the loop 16. 100

110 It will be apparent that when the parts are all positioned as shown and described the apparatus in the booth can be operated in the usual manner without interfering in any way with the movements of the operator. If, however, a film should become ignited in either of the projecting machines or at the rewinder F, one of the anchors 27 or 41 would likewise become ignited and thus release the cord attached thereto. As before 115 explained should the cord 30 be released at either end or should the cord 34 be released the weighted end of lever 19 will promptly fall because the cords will tend to straighten out and thereby relieve the weighted end of 120 125 130

lever 19 from its support. As soon as this lever is actuated under its weight 22 the nose 21 will be lifted out of the loop 16 and as there is a constant pull upon this loop through the different cords attached to it, said loop, when released, will promptly slide along finger 15 and onto the wire 5. Thus all of the shutters will close by gravity, the weighted member 47 in the switch box D will drop and break the circuit to the projecting machine and the weighted member 51 will drop and close the circuit to an exhaust fan, not shown, whereby fumes generated in the booth can be withdrawn. Cord 45 will also be released with the result that weight 44' will drop and valve 48' will open. Consequently jets of fire extinguishing fluid will be directed into the projecting machines or at any other points where nozzles may be located in the booth.

If desired either of the switch members 47 and 51, when actuated by its weight, can be utilized for turning on the lights in the house.

In the event of an emergency not caused by the ignition of a film or in the event of failure of the ignited film to release the mechanism, the operator in the booth, by pulling on the cord 14, can actuate the cam lever 12. Thus the lever will press against ledge 11 and thrust the slide 6 downwardly with the result that the loop 16 will be pressed off of the nose 21 and the various cords thus be actuated as heretofore explained to permit closing of the shutters, etc.

A main switch can be located in the booth A at the box E whereby the current can be controlled by the operator whenever desired.

What is claimed is:

1. The combination with a support, a member suspended therefrom and mounted for sliding movement relative thereto, gravity operated elements, and supporting connections between said elements and the suspended member, of a gravity operated lever, and means for holding said lever out of normal position and in engagement with the supported slidable member, said means including a highly combustible portion.

2. The combination with a weighted lever and cooperating means for holding the lever against movement under the action of its weight, said means including highly combustible portions, of a support, a member mounted to slide thereon and normally restrained by the lever, a gravity operated member, and a supporting connection between said member and the member engaged by the lever.

3. The combination with a latch lever having a weight at one end, of cooperating flexible means for holding the weighted end of the lever normally elevated, said holding

means including a plurality of highly combustible anchors, a slidably supported member normally restrained by the supported latch lever, a plurality of gravity operated members, and flexible supporting connections between said members and the restrained slidable member.

4. The combination with a latch lever having a weight at one end, of cooperating flexible means for holding the weighted end of the lever normally elevated, said holding means including a plurality of highly combustible anchors, a slidably supported member normally restrained by the supported latch lever, a plurality of gravity operated members, flexible supporting connections between said members and the restrained slidable member, and means under the control of an operator for disengaging said slidable member from the lever.

5. The combination with an enclosure having port holes and gravity operated shutters for closing the same, of a latch lever having a weighted end, flexible means for normally supporting the weighted end, said means including highly inflammable anchors and holding devices engaged by the anchors, a loop, means for supporting the loop for sliding movement, said loop being normally engaged and restrained by the lever, and flexible supporting connections between the shutters and the loop.

6. The combination with an enclosure and a film holding means therein, of a highly inflammable looped strip constituting an anchor, means for engaging the anchor at a point adjacent the held film, a weighted latch lever, a flexible connection between the weighted end of said lever and the anchor for holding the weighted end normally elevated, a gravity operated safety device, and means normally restrained by the latch lever for releasing the safety device when the lever is actuated by its weight.

7. In apparatus of the class described an attaching plate, a tongue depending therefrom having a slot, a supporting finger, a loop normally extended through the slot, a bail projecting therefrom in sliding engagement with the finger, a lever having a weighted arm, said lever being supported by the attaching plate, means on the lever for engaging the loop to hold it against sliding movement, means including a highly inflammable portion, for holding the lever against movement by its weight, and a safety device connected to the loop, said lever, when actuated by its weight constituting means for releasing the loop to permit actuation of the safety device.

In testimony that I claim the foregoing as my own, I have hereto affixed my signature.

GEORGE A. MEARS.
